(57) **CLAIM**

We claim the ornamental design for a TV receiver, as shown.

DESCRIPTION

FIG. 1 is a front/right-side/top perspective view of a TV receiver showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof; and,

FIG. 7 is a bottom-side elevational view thereof.

The broken lines in the drawing depict environmental subject matter only and form no part of the claimed design.
